UNITED STATES PATENT OFFICE

104,615

DESIGN FOR AN ACCORDION OR THE LIKE

John M. Miller, Arlington, Va.

Application February 21, 1936, Serial No. 61,291

Term of patent 3½ years

To all whom it may concern:

Be it known that I, John M. Miller, a citizen of the United States, residing at Arlington, Virginia, have invented a new, original, and ornamental Design for Accordions or the like, of which the following is a specification, reference being had to the accompanying drawing, forming a part thereof.

showing my design, Fig. 2 is a side elevation of an accordion, and Fig. 3 is a top plan view of an accordion.

The characteristic feature of my invention lies in the general contour of the accordion.

I claim as my invention:

The ornamental design for an accordion or the like as shown and described.

JOHN M. MILLER.
